CLAIM

The ornamental design for the food storage container, as shown and described.

DESCRIPTION

FIG. 1 is a perspective view of the food storage container showing my new design view;

FIG. 2 is a front elevational view thereof;

FIG. 3 is a rear elevational view thereof;

FIG. 4 is a left side elevational view thereof, where the right elevational view is symmetrical with the left elevational view;

FIG. 5 is a top plan view thereof;

FIG. 6 is a bottom plan view thereof; and,

FIG. 7 is a reference view thereof which shows a state that a lid and a container are separated.
